ROADBED EQUIPMENT AND METHOD OF USING THE SAME

Filed Oct. 31, 1929

UNITED STATES PATENT OFFICE

SVERRE ALFRED MORK, OF WASHINGTON, DISTRICT OF COLUMBIA

ROADBED EQUIPMENT AND METHOD OF USING THE SAME

Application filed October 31, 1929. Serial No. 403,849.

My invention, forming the subject-matter of this specification, relates generally to molded rail ties and the method of fastening rails thereto.

5 Maintenance of roadbed for railways has generally employed wooden ties and, due to the growing scarcity of suitable wood, and the increased expense, resort has been had to the wood substitutes such as concrete or 10 other plastic material which will set and become hard after molding. The concrete ties are necessarily heavy and difficult to handle and also present difficulties due to breakage. Such breakage is occasioned by expansion of 15 wooden inserts placed in the molded tie to receive fastening devices and by shock and jar incident to driving standard fastening devices into such inserts. The rigid concrete tie has a tendency to break at the center portion due to stresses set up by trains and such 20 ties do not afford the desired elasticity in the roadbed.

This invention contemplates the manufacture of a molded concrete tie made in separate 25 sections held in spaced relation by a hinge joint permitting relative movement of the sections but preventing contact of the molded sections with each other when in use. The sections are duplicates enabling them to 30 be used on either side of the roadbed in interchangeable relationship. The invention also contemplates the provision of metal inserts in the tie sections for holding any type of standard fastening means. The inserts 35 are formed of metal or metal compositions which are easily fusible under the influence of heat applied thereto so that the fastening members, of whatever type employed, may be anchored in the inserts without shock 40 or jar attending the ordinary driving or forcing of such fastening device into the tie or inserts provided. The invention also contemplates the novel method of fastening standard rails to the ties by standard rail spikes 45 or lag screws and involves no change in the character of such elements. The method comprises applying heat to the fusible metal insert in any well known manner, preferably by using an electric circuit and a source of 50 electrical energy. When an electric circuit

is employed one side of the circuit will be connected with the fusible metal and the other side with the fastening element, so that the heating of the fusible metal will allow the fastening element to enter the metal and be 55 firmly retained therein when the metal cools. This method minimizes replacements and breakage and facilitates easy and inexpensive maintenance of roadbed equipment. For example, rails may be fastened or the fastening 60 tightened by using any source of electrical energy suitable to heat the fusible metal.

Among the objects of this invention is the provision of a molded tie structure, sections 65 of which are hinged together to afford the desired elasticity yet retaining all of the well known advantages of the concrete tie with elimination of the tendency of breakage at the center portions of such ties.

A further object of the invention is the provision of a tie structure in which duplicate sections may be employed in interchangeable relationship, and the elimination of wood inserts and the like, to receive fastening means.

A further object of the invention is the provision of a simple anchoring means into which standard rail fastening elements may be forced without jar or shock liable to injure the tie structure.

Still a further object of the invention is the provision of a novel method of fastening rails to the tie sections and the method of easily tightening the fastenings of rails by the application of heat to fusible means serving to anchor fastening elements in the tie.

The rail tie and method of this invention is hereinafter disclosed in a preferred embodiment, for purposes of illustration, by the specification and drawings forming a part 90 thereof.

In the drawings, wherein like reference numerals designate corresponding parts throughout the several figures,—

Figure 1 is a side elevational plan view of 95 a complete tie assembly in accordance with the invention, showing rails mounted thereon.

Fig. 2 is a top plan view of the tie assembly of Fig. 1.

Fig. 3 is a longitudinal sectional view of one of the tie elements showing the reinforcing elements, hinge structure, and the fusible metal anchoring means employed. This figure is also a diagrammatic showing of one manner of application of an electrical current employed to heat the fusible elements.

Fig. 4 is a transverse sectional view through one of the tie section taken on the line 4-4 of Fig. 1.

Fig. 5 is a perspective view of one of the hinge elements employed.

With reference to the drawings, a complete rail tie in accordance with the invention comprises two duplicate complementary tie sections 1 and 2, formed from some suitable plastic material such as concrete, fastened together by a pivot or hinge structure 3, interposed between adjacent ends of the sections. It is desirable in the complete assembly, that the ends of the complementary concrete sections be kept from contact with each other to avoid breakage which is accomplished in the present structure by having the pivot or hinge members 4 of each tie section project beyond the end of the molded portion of the section. The ends of the tie sections which are pivoted are suitably cut away, as at 5, to provide clearance permitting the tie sections to move about the pivot 3 without bringing the concrete portions into engagement. To provide for the direct fastening of respective tie sections to limit pivotal movement, each section may be equipped with a combined reinforcing and fastening member 6 imbedded in the concrete and projecting at the pivotal end of the section. The combined reinforcing and fastening members may be fastened relative to each other by any suitable fastening means such as a key or an ordinary bolt.

Each tie section comprises a body of suitable material such as concrete, including suitable reinforcing elements 7 which are shown in the drawing for purpose of illustration as comprising U-shaped members disposed horizontally in the tie section, substantially parallel with the sides thereof, in the upper and lower portions of the section.

Combined reinforcing and hinge elements 4 are molded in each section, said elements being shown in the form of apertured straps having one end bent back to form a hinge loop to accommodate a hinge pin or king bolt 8, when the section is assembled with a duplicate section to form a complete tie unit. The hinge elements are so spaced and located, that each tie section is capable of being used on either side of the roadbed. The hinge elements 4 project beyond the molded portions of each section a sufficient distance to preclude contact of the molded portion of the tie section with that of a complementary section when such sections are in use fastened together by a hinge pin or king bolt passed

through the loop of the hinge elements. It will be understood, in bringing together complementary tie sections, that the hinge elements are brought into registry and overlapping relation to receive the hinge pin or king bolt.

The imbedded hinge elements 4 have their inner apertured ends connected with the respective ends of U-shaped reinforcing members 9 and 10 in the body of the tie section. These reinforcing elements may, if desired, be formed integral with the hinge elements, but in the preferred form of the invention illustrated, are shown as separate reinforcing elements fastened to the hinge members. The reinforcing members 9 and 10 are disposed diagonally in the molded sections entering the lower ends of spaced recesses or wells 12 formed in the body of the tie section, the purpose of which will be presently described.

The recesses or wells 12 open through the upper surface of the tie and extend downwardly into the tie body a distance sufficient to accommodate a standard type of rail fastening element 13. The wells are filled with material 14, preferably metal such as babbitt, which is easily fusible under the influence of applied heat and it is essential that each well be formed by undercut portions in the tie sections to provide suitable anchorage in the tie. Many forms for anchoring the metal in the body of the tie will occur to those skilled in the art. The preferred and simple form selected for illustration shows the walls defining the recesses or wells diverging from the upper surface of the tie to form a well larger at the bottom than at the top. The spacing of the recesses, is determined longitudinally of the tie section by the width of the base of the rail to be accommodated, and laterally of the tie section by the number of fastening points desired for the rail.

In the drawings, there is shown a conventional rail plate 15 separated from the concrete tie by the insulation element 21 and having a rail 16 resting on the plate in assembled position. The apertures in the rail plate for receiving fastening devices are shown in registry with the wells provided in the tie so that the rail binding element, of whatever form employed, may be inserted through the plate and into contact with the metal provided in the wells of the tie section. The insulation element 21 forms an elastic joint between the metal surfaces of the rail or rail support and the tie. This provision minimizes the traction noises and the attrition of the metal elements on the concrete of the tie. The insulation 21 is preferably composed of a composition of asphalt and some fiber preferably asbestos. The asphalt and asbestos combination is at all times waterproof and forms a medium which will provide a permanent base. In the case of wood,

paper and such material, moisture soon causes disintegration necessitating replacement. The use of asbestos and asphalt has a stable characteristic and affords excellent insulation for the purpose. The contact of the asphalt with the metal tends to preserve the metal and its resistance to moisture prevents rust at the bearing points on the tie.

The method of fastening and tightening rails to the respective tie sections is described with particular reference to Fig. 3 of the drawing. A source of electrical energy 17, diagrammatically shown as a battery in the drawing, has one side of the output connected by the lead 18 extending to the hinge connection between the tie sections, and the other side connected by conductor 19 to any suitable means to make contact with the rail fastening member 13. Thus connected, a circuit will be established from the source of electrical energy 17, by way of the fastening element 13, fusible metal 14, reinforcing rods and hinge element 4, to the other side of the source of energy. It will be understood, by those skilled in the art, that any scheme of connections which brings opposite sides of a suitable source of energy to the fastening element and the fusible metal will suffice, when the circuit is closed to melt the fusible metal allowing the fastening element to be forced into the softened metal to the fastening position where it is held until the metal cools. With the fastening element extended into the softened metal, the circuit is broken and the metal is allowed to rapidly cool, thus imbedding and securely holding the fastening element in position. The usual rough surface of standard fastening devices is sufficient to present anchoring voids into which the softened metal flows to securely bind when cool. Fastening devices having mutilated surfaces or screw threads are very firmly anchored by the fusible metal.

In building and maintaining roadbed using the device and method of the invention, many advantages become apparent from the description. For example, energy for fusing the metal in the ties may be obtained from suitable portable machine or vehicle designed for transport along the track; or any other source for applying heat may be employed. If it should become necessary to replace one of the tie sections, such replacement may be made without removing the counterpart section and should it become necessary to tighten loosened rails, it is only necessary to apply heat to the fusible metal and pressure to the parts to procure the degree of tightness desired. Removal of parts and replacements are minimized by the tightening method described and handling and transportation difficulties are solved by the employment of duplicate counterpart tie sections of relatively small weight.

The applicant has described his invention

as required by the statutes as applied to a specific rail fastening arrangement disclosed by the drawing, but it is to be understood that the invention is capable of more general application than the specific embodiment selected for illustration. The invention is not limited to the specific form selected for illustration except for such limitations as the appended claims may impart.

I claim:

1. In a device of the character described, a molded concrete body, and means imbedded in the body easily fusible under the influence of heat for anchoring fastening elements.

2. In a device of the character described, a molded reinforced concrete body having a flat seat portion and spaced pockets, and fusible metal disposed in the pockets adapted to receive and anchor rail fastening elements.

3. In a device of the character described, a molded concrete body provided with a rail seat and having spaced recesses formed therein, reinforcing means imbedded in the concrete body, said means having portions exposed in the recesses and portions extending beyond the body, and fusible metal in the recesses in contact with said reinforcing means.

4. A roadbed assembly comprising a rail, a molded concrete tie provided with a seat portion to support the rail, fusible metal imbedded in the tie, a rail plate, an asphalt and fibre body interposed between the said plate and the concrete tie, and rail fastening elements engaging the rail and anchored in the fusible metal.

5. In combination, a reinforced concrete tie having spaced recesses formed therein, fusible metal in the recesses, a rail, and fastening means engaging the rail and anchored in the fusible metal.

6. In combination, a reinforced concrete tie having spaced recesses formed therein, fusible metal in the recesses, a rail, an asphalt and fibre composition between the rail and concrete tie, and rail fastening means engaging the rail and anchored in the fusible metal for binding the elements together.

7. The method of fastening rails to concrete ties having fusible metal sections which comprises, applying heat to the metal sections, forcing a fastening device into the metal while heated, and allowing the metal to cool to firmly engage the fastening device.

8. The method of anchoring members to concrete bodies having fusible metal imbedded therein which comprises, fusing the metal by an electric current, forcing a fastening element into engagement with the metal and within the fusible metal, and allowing the metal to cool to firmly engage the fastening device.

9. The method of tightening a fastening for a rail and concrete tie having fusible metal sections which comprises, simulta-

neously applying heat to the fusible metal and positioning force to the fastening means, discontinuing the application of heat, and maintaining the positioning force until the fusible metal cools.

- 5 10. In combination, two molded concrete members, each member having spaced recesses formed therein and fusible metal disposed in the recesses to receive fastening elements, and combined metallic reinforcing and connecting means conductive of an electric current imbedded in the members and extending into contact with the fusible metal in the recesses in each member, said reinforcing and connecting means including a pivotal connection intermediate the members, whereby said means and the fusible metal may pass an electric current when used to melt the fusible metal.
- 10 15. 11. A molded reinforced concrete support comprising counterpart molded bodies, metal fastening means for connecting ends of the bodies to permit relative movement of the bodies, means easily fusible under the influence of heat in each body for receiving and retaining rail fastening elements, and metallic conductors connecting the fastening means and fusible means to provide electrical connection between the fusible elements in the counterpart molded bodies.
- 20 25. 12. In a device of the character described, molded concrete members each provided with a rail seat and spaced recesses formed therein, fusible metal in the recesses, metallic reinforcing means imbedded in each of the members, said means having portions disposed in the recesses in contact with the fusible metal and portions extending beyond the end of the member, means conductively connecting the extending portions from each member together to permit relative movement of the members, and to provide conductive connection between fusible metal in the members.
- 30 35. 40. 45. In testimony whereof I have hereunto subscribed my name.

SVERRE ALFRED MORK.
